UNITED STATES PATENT OFFICE.

JOHN HAYS HAMMOND, JR., OF GLOUCESTER, MASSACHUSETTS.

SYSTEM OF GUIDE LIGHTS.

Application filed February 26, 1920, Serial No. 361,408. Renewed May 5, 1923.

Some of the objects of the present invention are to provide means for determining the course of a moving body from a distant point of observation; to provide means for indicating the position and course of a marine body at night; to provide means for indicating in a predetermined manner any one of a plurality of courses of a moving marine body; to provide means for changing 10 a signal on a vessel in accordance with a change of the course of the vessel whereby a plurality of predetermined signals can be separately set to indicate the true course of the vessel at any time; to 15 provide a plurality of guide lights arranged to be separately lighted in predetermined combinations arranged with respect to different courses of the vessel whereby any lighted combination identifies the true course 20 of the vessel; and to provide other improvements as will hereinafter appear.

In the accompanying drawings Fig. 1 represents a perspective of a marine vessel equipped with guide lights embodying one 25 form of the present invention; Fig. 2 represents the guide lights at night as they appear in several running positions of the vessel, the arrows indicating the several directions with respect to a common point of observation; and Fig. 3 is a diagram of the 30 wiring for the several circuits.

Referring to the drawings one form of the present invention comprises a system of guide lights mounted upon a movable body 35 such as a boat, torpedo or any other suitable body, the movements of which are to be observed from a distant point.

For the purpose of distinguishing the bow from the stern of the boat 10, when the boat 40 is operating at night, there is a mast 11 fixedly mounted in a vertical position adjacent the bow of the boat 10 while a similar mast 12 is mounted in a vertical position adjacent the stern of the boat. The two masts 11 45 and 12 are preferably spaced a distance which will permit their relative positions to be readily determined by an observer at a distant station. The mast 11 is provided with a set of lights 13, which, in the 50 preferred form, are located at the top of the mast 11 or in close proximity thereto. The mast 12 is provided with a plurality of sets of lights 14, 15 and 16, the set 14 being preferably at the top of the mast 12 or in close 55 proximity thereto, the set 16 in relatively close proximity to the bottom of the mast

12, while the set 15 is interposed between the two.

In order that the bow of the boat 10 may be readily identified in any running position 60 of the boat the set of lights 13 comprises four lamps, 20, 21, 22 and 23 two of which, 20 and 22, are arranged horizontally in aligned relation parallel to the longitudinal axis of the boat 10, while the lamps 21 and 65 23 are also horizontally disposed and in aligned relation but at right angles to the aforesaid axis.

As a means for limiting the area of the beam of light projected from each of the 70 lamps, each lamp is enclosed within a reflecting shield 24, the sides of which diverge respectively at such an angle and the arrangement is such that the shield 24 for the lamp 20 projects its beam 45° to the left of 75 the bow of the boat and 45° to the right of the bow, similarly the port lamp 21 has its beam projected by reflector 24 through a 90° quadrant between the beams of the lamps 20 and 22; the lamp 22 has its beam projected 80 by its reflector 24, 45° to the left of the stern and 45° to the right of the stern of the boat; and the lamp 23 has its beam projected by its reflector 24 through a quadrant of 90° 85 between the beams of the lamps 20 and 22.

As a further means of identifying the stern mast 12 from the bow mast 11 and providing for a definite combination of light signals with the lights 13 on the mast 11, the set of lights 14 comprises two lamps 25 90 and 26 arranged in horizontal alignment with their common axis perpendicular to the longitudinal axis of the boat 10. Each of the lamps 25 and 26 is provided with a reflector which is preferably of the same type 95 as that described in connection with the set of lights 13 and for this reason each of these reflectors will be identified by the same reference numeral 24 and the construction will be understood to be such as to project a beam of light from each of the lamps in a 90° quadrant, the one beam showing from the port side and the other from the starboard side of the boat 10. The set of lights 15 consists, in the present instance, of a pair of 100 lamps 30 and 31 arranged in a similar manner to the lamps 25 and 26 and enclosed respectively in like reflectors 24, but in addition has a third lamp 32 pointing toward 105 the bow of the boat and enclosed in a reflector 24 so that its beam of light is projected forwardly in a quadrant 45° to the 110

right and 45° to the left of the longitudinal axis of the boat 10. The set of lights 16 consists of three lamps 33, 34 and 35 arranged in a similar manner to the set of 5 lights 15, each likewise having a reflector 24, but in addition there is a lamp 36 pointing toward the stern of the boat and having a reflector 24 which projects the beam of light in a quadrant 45° to the right and 45° to 10 the left of the longitudinal axis of the boat 10.

From the foregoing it will be evident that the arrangement of the several sets of lamps is such that combination light effects may be 15 arranged, each combination representing a definite direction of movement of the boat. Thus by reference to Fig. 2 it will be seen that when the boat is in position A and travelling in the direction of the arrow A, 20 or within the dotted lines the combination of lights identifying this direction of movement will be lamp 23 of the forward mast 11 and lamps 26, 31 and 34 of the respective sets of lights 14, 15 and 16; when the boat is 25 travelling in the direction B as indicated by arrow B, or within the dotted lines the combination of lights is lamp 20 of the set 13 and the lamps 32 and 35 of the respective sets 15 and 16; when the boat is in position C 30 travelling in the direction of arrow C, or within the dotted lines the combination of lights is the lamp 21 of the forward set 13 and lamps 25, 30 and 33 of the respective set of lights 14, 15 and 16; and when the 35 boat is proceeding in the direction D, as indicated by arrow D, or within the dotted lines but two lamps are shown, the lamp 22 of the forward set of lights 13 and the lamp 36 of the rear set 16.

40 Therefore to an observer stationed at a distant point it is possible to tell exactly not only the position of the boat but also the course it is following whether moving towards or away from the observer, or at an 45 angle to such courses or in a course broad-side to the observer. For example when two lights one above another and a third light to one side are visible the observer, knowing the predetermined signal, is advised that the 50 boat is moving toward the observer on a course forming an angle of less than forty-five degrees on either side of the line of observation (B Fig. 2). Similarly the remaining combinations of lights are respectively predetermined for certain courses and hence the observer is advised at all times as to the true course of the boat. In addition to keeping the observer informed as to the boat's course and direction the reflectors 55 24 prevent the lighted lamps from being visible except within the prescribed area of observation and no lights are visible from the opposite side of the boat at all, or outside of a 90° quadrant.

60 65 For the purpose of lighting the several

lamps above described electric means are preferably employed and in the present instance a battery 40 is arranged to supply current to all of the lamps by way of leads 41 and 42 from one side of the battery 40, 70 the lead 41 connecting the lamps of the set 13 in multiple and the lead 42 connecting the lamps of the sets 14, 15 and 16 in multiples.

In order to cause only one combination of 75 certain predetermined combinations of the lamps of the several sets to be lighted at a time, the other side of the battery 40 has a lead 43 connected to a brush contactor 44 which is arranged to bear against the outer periphery of a cylindrical hub 45 of conducting material. To this hub 45 a radially disposed arm 46 is rigidly secured to form one terminal of a number of possible circuits 80 which are separately closed when the arm 46 is moved into contact with any one of four segments 50, 51, 52 and 53, each of which is of conducting material located in the path of the arm 46 and insulated one from another by insulating blocks 54. The segment 50 has a lead 55 arranged to complete the multiple circuit including the lamps 23, 26, 31 and 34 whenever the arm 46 rests in contact with the said segment 50; the segment 51 has a lead 56 arranged to complete the multiple circuit including the lamps 20, 32 and 35 whenever the arm 46 rests in contact with the said segment 51; the segment 52 has a lead 57 arranged to complete the multiple circuit including the lamps 21, 25, 30 and 33 whenever the arm 46 rests in contact with the said segment 52; and the segment 53 has a lead 58 arranged to complete the multiple circuit including the lamps 22 and 36 whenever the arm 46 rests 95 in contact with the segment 53.

For causing the respective combinations of lamps to light in accordance with predetermined positions of the boat considered with respect to the vertical axis of the boat, the series of segments 50, 51, 52 and 53 are fixed in any suitable manner to the body of the boat 10 while the hub 45 and arm 46 are fast to a rod 60 as an axis which is maintained fixed in space by a gyroscope in a well known manner. Thus any deviation of the boat about a vertical axis will cause the segments 50, 51, 52 and 53 to move with respect to the arm 46, thereby bringing the contactor arm 46 into contact with the respective segments one after another in accordance with the angular deviation. As each segment is engaged by the contactor arm 46 the lights of the combination corresponding to the last direction of movement of the boat are extinguished and are immediately replaced by the new combination which corresponds to the new course of the boat.

From the foregoing it will be apparent 100 that a complete unitary system of guide 105

lights has been devised whereby the position and course of a distant movable body, such as a boat or torpedo which is arranged to be controlled from a distant station, is always known to the observer at that station. By providing a plurality of predetermined indicating signals, one for every possible direction of movement of the body and arranging a system for automatically changing from one signal to the other in accordance with a change of course of the body, it is possible to accurately follow the course of the body at night. Furthermore the signals displayed are only visible within a pre-scribed area within the field of vision of the observer and consequently enemy observers outside of this restricted area are kept in ignorance of the approach or movements of the boat.

While but one of the many forms of the present invention are here shown and described, it will be understood that the invention might be embodied in many other forms without departing from the present invention or the scope of the appended claims.

Having thus described my invention, I

claim and desire to protect by Letters Patent of the United States:

1. In a system of guide lights, a movable body, a plurality of different combinations of lamps mounted on said body, each combination corresponding to a predetermined direction of movement of said body, means to automatically select the combination corresponding to the course of said body, and means to light only the lamps of the selected combination.
2. In a system of guide lights, a movable body, a plurality of different combinations of lamps mounted on said body, each combination corresponding to a predetermined direction of movement of said body, means to automatically select the combination corresponding to the course of said body, means to light only the lamps of the selected combination, and means to limit the beams of light from said selected combination to a prescribed area.

Signed at Gloucester in the county of Essex and State of Mass., this 14th day of Feb. A. D. 1920.

JOHN HAYS HAMMOND, JR.
